UNITED STATES PATENT OFFICE.

WILLIAM M. EVENSEN, OF CHICAGO, ILLINOIS, ASSIGNOR TO GOSS PRINTING PRESS COMPANY, OF CHICAGO, ILLINOIS, A CORPORATION OF ILLINOIS.

PRINTING-PLATE CLAMP.

1,350,015.

Specification of Letters Patent. Patented Aug. 17, 1920.

Application filed November 6, 1917, Serial No. 200,501. Renewed January 8, 1919. Serial No. 270,213.

To all whom it may concern:

Be it known that I, WILLIAM M. EVENSEN, a citizen of the United States, residing at Chicago, county of Cook, and State of Illinois, have invented certain new and useful Improvements in Printing-Plate Clamps, of which the following is a specification.

The invention relates to adjustable plate clamps, such as are used in positioning and holding in position electrotype, stereotype and other plates upon the cylinder or other form bearing member of a printing press.

The invention consists in the novel articles, parts, constructions, arrangements, combinations and improvements herein shown and described.

The objects and advantages of the invention will be set forth in part hereinafter, and in part will be obvious herefrom, or may be learned by practice with the invention; the same being realized and attained through the means, instrumentalities and combinations pointed out in the appended claims.

The accompanying drawings, referred to herein and constituting a part hereof, illustrate one embodiment of the invention, and together with the description serve to illustrate the principles thereof.

Of the drawings:

Figure 1 is a side elevation of the clamp in place in a slot in the press bed and engaging the plate, the plate and bed being shown in section;

Fig. 2 is an end elevation of the clamp alone, looking thereat from the left in Fig. 1, and showing a curved plate jaw;

Fig. 3 is a transverse central section through the clamp taken on line 3—3 of Fig. 1 and looking in the direction of the arrows, and showing the bed in section and the plate in elevation;

Fig. 4 is a detail elevation of the expanding screw; and

Fig. 5 is an isometric detail of the wedge piece coöperating with the clamp body.

Referring more particularly to the accompanying drawings, illustrating by way of example the present preferred embodiment of the invention, the clamping jaw or plate engaging member 1 is provided with an undercut edge 2, adapted to take over and engage with the beveled edge 3 of the plate 4, which plate rests upon the bed 5 of

the press. As embodied, the body 6 of the plate clamp is integral with the clamping jaw 1, the body of the clamp extending downwardly into the slot 7 in the bed 5. The body 6 of the clamp is formed in its upper part to substantially fill the slot 7, the slot being preferably undercut or dovetailed, being wider in cross section at the bottom than the top, and having its sides sloping uniformly upwardly toward each other.

In the upper portion of the body 6 is an internally screwthreaded hole 9 adapted to receive the screwthreads on the body 10 of the clamping screw. The clamping screw is provided with an enlarged, conically shaped head 11, which head is at the lower end and within the slot 7 in the bed plate. The tip or upper end of the screw is provided with a slot 12, by which a screw driver may be employed to turn the screw and thus move it upwardly and downwardly with respect to the body 6 of the plate clamp. The body of the plate clamp, in the downwardly depending portion 13 is cut out hemi-conically, or formed to fit closely the tapered or conical head of the clamping screw (see Fig. 3).

The clamp body 6 is longitudinally recessed substantially centrally from the bottom upwardly for a portion of the depth of the body and then outwardly to one side. The expanding member rests within this recess and is approximately of the same shape as the recess. The clamp body and expanding member are forced apart to fix the clamp in position in the slot. The expanding member 14 which coöperates with the clamp body as stated to hold the clamp in position in the slot, as embodied consists of an elongated member or bar shaped substantially in cross section to fit into the recess in the slot between the upper portion and the downwardly depending portion of the clamp body, and preferably of the same length with the body of the clamp. This coöperating clamping or expanding member is shaped or hollowed on its inner side at 15 into hemi-conical form to coöperate with the tapered or conical head 11 of the expanding screw.

The operation of the clamp will be readily understood. A screw driver is inserted into the slot 12 of the expanding screw, which is always accessible from the top of the clamp. As the screw is turned and thus

moves upwardly, the conical head 11 thereof drives the coöperating expanding member 14 away transversely from the body of the clamp, thereby firmly wedging the 5 clamp in the groove in the bed. By turning the screw in the opposite direction, the clamp is loosened and may be slid along the groove.

The clamp is of a very simple and sturdy 10 construction, having but two parts besides the screw. The coöperating clamping members are simple, solid and strong. The body of the clamp is very large, occupying the greater part of the cross-sectional space in 15 the groove in the plate bed, and the coöperating expanding member is also simple and strong. The clamp body and head being integral gives a very strong construction, and the large size of the clamping body also 20 serves to protect it during the hard usage given to clamps by many pressmen, as for instance driving clamps along the groove after they have been screwed up quite tightly into clamping position. The clamp- 25 ing screw cannot come out of the clamp and cause damage to the press or plates. There is also great advantage in the utilization of the headless screws, as the breaking off of the screwheads with consequent damage of 30 the press or plates, and the screw is at all times inside of the clamp. Other advantages will be obvious herefrom or may be learned by practice with the invention.

It will be understood that changes may 35 be made from the details of construction as shown and described, within the scope of the accompanying claims, without departing from the principles of the invention and without sacrificing its chief advantages.

40 What I claim as my invention and desire to secure by Letters Patent is:

1. A printing plate clamp adapted to co- 45 operate with a slotted plate bed, and including in combination a clamping jaw, a clamp body attached thereto and extending into a slot in the bed, the clamp body being longitudinally recessed from the center thereof to one side, an expanding member substantially of the shape of the recess in the clamp 50 body and located in said recess, the adjacent upright faces of the body and expanding member having corresponding hemi-conical recesses therein terminating in a screw-threaded aperture through the clamp body, 55 and an expanding screw having a conical head in said hemi-conical recess and its shank threaded into the screw-threaded aperture in the clamp body.

2. A printing plate clamp adapted to co- 60 operate with a slotted plate bed, and including in combination a clamping jaw, a clamp body attached thereto outwardly tapering away from the clamp and extending into a slot in the bed, the clamp body being longitudinally recessed from the center thereof 65

to one side, an expanding member substantially of the shape of the recess in the clamp body and located in said recess, the adjacent upright faces of the body and expanding member having corresponding hemi- 70 conical recesses therein terminating in a screw-threaded aperture, through the clamp body, and an expanding screw having a conical head in said hemi-conical recess and its shank threaded into the screw-threaded 75 aperture in the clamp body.

3. A printing plate clamp adapted to co- 80 operate with a slotted bed and comprising a clamping jaw, a clamp body in fixed relation thereto and extending into a slot in the bed, a vertically disposed expanding screw threaded in the clamp body, and an expanding member in the slot beside the clamp body and directly engaged by the screw to hold the clamp in position in the slot. 85

4. A printing plate clamp adapted to co- 90 operate with a slotted bed and comprising a clamping jaw, a clamp body in fixed relation thereto and extending into a slot in the bed, a vertically disposed expanding screw threaded in the clamp body, and an expanding member partly beneath and partly alongside the clamp body and acted upon by the screw to coöperate with the clamp body to hold the clamp in position in the slot. 95

5. A printing plate clamp adapted to co- 100 operate with a slotted bed and comprising only three separate parts, including a clamping jaw, a clamp body in fixed relation thereto and extending into a slot in the bed, a vertically disposed expanding screw threaded in the clamp body, and having an enlarged head at the bottom thereof, and an expanding member in the slot beside the clamp body, the screw head directly engaging the clamp body and an expanding member to effect the expanding action for holding 105 the clamp in position in the slot.

6. A printing plate clamp adapted to co- 110 operate with a slotted bed and comprising a clamping jaw, a clamp body attached thereto and extending into a slot in the bed, a vertically disposed expanding screw threaded in the clamp body, and having a conical head at the bottom thereof, and an expanding 115 member in the slot beside the clamp body, the clamp body and expanding members having hemi-conically shaped portions coöperating with the conical screw head, the screw head directly engaging the clamp body and expanding member to effect the expanding action for holding the clamp in position in the slot. 120

7. A printing plate clamp adapted to co- 125 operate with a slotted bed and comprising a clamping jaw, a clamp body in fixed relation thereto and extending into a slot in the bed, a vertically disposed expanding screw threaded in the clamp body, and having turning means at its upper end at the top of 130

- the clamp body, and an expanding member in the slot beside the clamp body and directly engaged by the screw to hold the clamp in position in the slot.
5. 8. A printing plate clamp adapted to co-operate with a slotted bed and comprising a clamping jaw, a clamp body in fixed relation thereto and extending into a slot in the bed, a vertically disposed expanding screw 10 threaded in the clamp body, and having turning means at its upper end at the top of the clamp body, and having an enlarged head at the bottom thereof, and an expanding member in the slot beside the clamp body, the screw head directly engaging the clamp body and expanding member to effect 15 the expanding action for holding the clamp in position in the slot.
9. A printing plate clamp adapted to co-operate with a slotted bed and comprising a clamping jaw, a clamp body attached thereto and extending into a slot in the bed, a vertically disposed expanding screw threaded 20 in the clamp body, and having turning means at its upper end at the top of the clamp body, and having a conical head at the bottom thereof, and an expanding member in the slot beside the clamp body, the clamp body and expanding members having 25 hemi-conically shaped portions co-operating with the conical screw head, the screw head directly engaging the clamp body and expanding member to effect the expanding action 30 for holding the clamp in position in the slot.
10. A printing plate clamp adapted to co-operate with a slotted bed, and including in combination a clamping jaw, a clamp body attached thereto and extending into a slot in the bed, the clamp body being longitudinally 35 recessed from the center thereof to one side, an expanding member substantially of the

shape of the recess in the clamp body and located in said recess, the adjacent upright faces of the body and expanding member 45

having corresponding hemi-cylindrical recesses therein and a vertically disposed screw-threaded aperture through the clamp body, and an expanding screw having a conical head at its bottom co-operating with 50 said hemi-cylindrical recesses and threaded in the aperture in the clamp body and having turning means at its upper end at the top surface of the clamp body.

11. A printing plate clamp adapted to co-operate with a slotted bed and including in combination a clamping jaw and a clamp body in fixed relation to the jaw and extending backwardly from the plate engaging edge thereof and extending into the slot 60 bed, a vertically disposed expanding screw threaded in the clamp body, and an expanding member in the slot beside the clamp body and directly engaged by the screw to hold the clamp in position in the slot. 65

12. A printing plate clamp adapted to co-operate with a slotted bed and including in combination a clamping jaw and a clamp body in fixed relation to the jaw arranged at right angles to and extending backwardly 70 from the plate engaging edge thereof and extending into the slot bed, a vertically disposed expanding screw threaded in the clamp body, and an expanding member in the slot beside the clamp body and directly 75 engaged by the screw to hold the clamp in position in the slot.

In testimony whereof, I have signed my name to this specification, in the presence of two subscribing witnesses.

WILLIAM M. EVENSEN.
